UNITED STATES PATENT OFFICE.

HENRY BARKSCHAT, OF LOS ANGELES, CALIFORNIA, ASSIGNOR TO MARBELITE CORPORATION OF AMERICA, OF LOS ANGELES, CALIFORNIA, A CORPORATION OF DELAWARE.

DESIGN FOR A POST.

Application filed March 29, 1926. Serial No. 17,098. Term of patent 14 years.

To all whom it may concern:

Be it known that I, HENRY BARKSCHAT, a citizen of the United States, residing at Los Angeles, in the county of Los Angeles, State of California, have invented a new, original, and ornamental Design for a Post, of which the following is a specification, reference being had to the accompanying drawing, forming a part thereof.

The figure is a perspective view of a post showing my new design.

I claim:

The ornamental design for a post, as shown.

HENRY BARKSCHAT.
